UNITED STATES PATENT OFFICE

WILLIAM PAULUS, OF BUFFALO, NEW YORK

DESIGN FOR A WINDSHIELD CLEANER MOTOR

Application filed February 17, 1932. Serial No. 42,910. Term of patent 3½ years.

To all whom it may concern:

Be it known that I, WILLIAM PAULUS, a citizen of the United States, residing at Buffalo, in the county of Erie and State of New York, have invented a new, original, and ornamental Design for a Windshield Cleaner Motor, of which the following is a specification, reference being had to the accompanying drawings, forming part thereof.

Fig. 1 is a front elevation of the ornamental design for windshield cleaner motors; and

Fig. 2 is a side view thereof.

I claim:

The ornamental design for a windshield cleaner motor, as shown.

WILLIAM PAULUS.
